UNITED STATES PATENT OFFICE.

TONY KUSNIERCZ, OF EASTHAMPTON, MASSACHUSETTS.

ANTISUBMARINE DEVICE.

1,299,962.

Specification of Letters Patent.

Patented Apr. 8, 1919.

Application filed November 12, 1918. Serial No. 262,121.

To all whom it may concern:

Be it known that I, TONY KUSNIERCZ, a subject of the Emperor of Austria, residing at Easthampton, county of Hampshire, and 5 State of Massachusetts, have invented certain new and useful Improvements in Anti-submarine Devices, of which the following is a specification.

This invention relates to improvements in 10 antitorpedo devices, as applied to sea going ships, and has as its special object, to provide means whereby the ship may be rendered invulnerable against the attacks of torpedoes, mines, and other like undersea 15 projectiles.

A further object is to provide a plurality of devices extending from the ship side, each independent of the other, but so correlated as to form an essential barrier against mis- 20 siles of the character mentioned.

These and other like objects are attained by the novel construction and combination of parts hereinafter described and shown in the accompanying drawings, forming a material 25 part of this disclosure, and in which:—

Figure 1 is a top plan view showing a conventional type of ship, and indicating the application of the invention.

Fig. 2 is a side elevational view of the 30 same, parts being broken away in order to show the interior construction.

Fig. 3 is a transverse sectional view taken on line 3—3 of Fig. 2.

Fig. 4 is an enlarged horizontal sectional 35 view taken on line 4—4 of Fig. 3, and,

Fig. 5 is a fragmentary side elevational view of one of the outermost guard elements.

Referring to the drawings, a conventional type of ship is indicated by the numeral 10, 40 the same being supplied with all the necessary mechanism and paraphernalia for the proper navigation of the ship. Attached to the hull 11, upon opposite sides, are a plurality of brackets 14 and 15, the same being 45 rigidly engaged at spaced intervals, one above the water line and the other below, as indicated.

Secured to the brackets are arms 16 and 17, the latter being the lowermost, these arms

extending outward to a considerable dis- 50 tance, and having between their extreme ends vertically disposed rollers 20, having annularly grooved ends 21, over which are trained cables 22, in such manner as to hold the rollers in relative juxtaposed position. 55

These cables extend from one set of arms to the other so as to present a substantially unbroken row of the vertical rollers from the stem to stern of the vessel, and at a considerable distance from the hull so as to ward 60 off the attacks of submarine missiles.

These rollers are preferably made of wood or other material which is relatively light in nature so as to act as floats, materially supporting the structure with which they are 65 engaged.

Inwardly of the row of the vertical floating rollers 20 and secured between the arms 16 and 17 are nets 25 suspended from rods 26, which are engaged with the respective 70 arms 16 and 17, these nets being of a character adapted to prevent the passage therethrough of small missiles which may by chance pass the guards 20.

At a point farther in, attached to the arms 75 16 and 17, are other longitudinal bars 28, and disposed between these bars are a plurality of vertically positioned coiled springs 30, placed closely together so as to effectually prevent the passage of missiles directed 80 against the hull.

From the foregoing it will be seen that effective protective devices have been disclosed, which will prevent the impact of an undersea projectile with the hull of the ship, 85 thereby insuring its safety upon the sea.

Having thus described my invention what I claim as new and desire to secure by Letters Patent is—

In an antisubmarine device, the combination with the hull of a ship and a plurality of brackets disposed below and above the water line on each side, of arms rigidly engaged with said brackets, said arms extending laterally outward, vertical floating 90 rollers engaged at the ends of said arms in a row, said rollers having their surfaces juxtaposed and flexibly connected together at 95

said tops and bottoms, rails secured to said arms within said row of floating rollers, netting on said rails extending from a point above to a distance below the water line, and 5 other series of rails attached to said arms, and a plurality of springs secured to the last named row of rails, said springs being ar-

ranged closely adjacent and disposed midway between said netting and the hull of said ship.

In testimony whereof I have affixed my signature.

10

TONY KUSNIERCZ.
